UNITED STATES PATENT OFFICE.

HOWARD E. EVERETT, OF ST. PAUL, MINNESOTA.

DAUBER.

Application filed April 3, 1922. Serial No. 548,962.

To all whom it may concern:

Be it known that I, HOWARD E. EVERETT, a citizen of the United States, residing at St. Paul, in the county of Ramsey and State of Minnesota, have invented certain new and useful Improvements in Daubers, of which the following is a specification.

My invention relates to daubers for applying blacking or polish to the surface to be polished, and more particularly to that type, 10 of daubers having magazine handles adapted to contain the blacking and also having handily operable means for distributing the blacking to the bristles of the dauber.

One of the difficulties met with in the construction of daubers of this type, is the evaporation of some ingredients of the blacking paste resulting in a hardening thereof, whereby the bristles become packed 20 and stiff and therefore useless.

Further, movable parts of the paste ejecting mechanism become gummed up and unmanageable.

It is an object of my invention to provide 25 an improved dauber of the class described, which is provided with humidifying elements both at the discharge end of the magazine and immediately above the volume of blacking paste within the magazine, so that 30 gradual hardening of the paste at these points is prevented.

A further object of my invention is the provision of ejecting mechanism of novel 35 construction, whereby when the supply of blacking paste is exhausted, the ejecting mechanism will be rendered automatically ineffective, a certain disconnection of parts taking place whereby the user will be apprized of the exhaustion of the supply.

With these and other ends in view the invention consists in the construction, combination and arrangement of parts herein- 40 after described and claimed.

In the drawings,

Figure 1, is a perspective view of my improved dauber.

Fig. 2, is a full sized side view of the invention, the lower portion thereof shown in section.

Fig. 3, is a vertical sectional view on a central line bisecting the dauber, the view being drawn to an enlarged scale and partly broken away.

Figs. 4, 5 and 6 are detail views.

The invention comprises a hollow handle portion 1, which constitutes the magazine, a

bristle supporting sleeve 2 and a closure cap 3.

The handle portion comprises a cylindrical container 4, of uniform internal diameter and having an inset flat top 5, whereby is formed the upwardly opening circular shallow cavity or chamber 6, over which telescopes by means of its annular downturned flange 7 the actuating cap 8.

Centrally the top 5 is perforated with a circular aperture 9. At its lower extremity the container is internally threaded as at a to threadedly engage with the sleeve 2, the upper circular edge 10 of the latter forming 70 an internal shoulder in the bore of the container. The outer diameter of the sleeve is somewhat less than that of the container, the sleeve being spun down to form a restricted neck or ferrule portion 11. Firmly 75 packed in the ferrule 11 are the dauber bristles 12 of approximately uniform length to form collectively a tuft having a flat end to facilitate application of the blacking, said bristles being packed around a centrally disposed tube 13 which forms a discharge duct 80 centrally of the body of bristles, said duct being in open communication with the interior of the container. Fitting telescopic- ally and frictionally over the lower end of 85 the container, and designed to freely receive the exposed portion of the sleeve and the protruding bristles, is the cap 3, the latter being formed preferably with a flat top 14.

Frictionally held in the bottom of the cap 90 and lying flatly on the innerside of the top 14 thereof, is the absorbent element 15 having an inner face in parallelism with the flat end of the bristle tuft, preferably of 95 felt or other loose fibered material adapted 95 to hold oil or water.

By having the end of the dauber parallel with the humidifying element, all bristles are equidistant therefrom and are therefore 100 evenly humidified, which would not be the case if the dauber were rounded or conic in shape. I have found that the greatest efficiency is secured with respect to applying blacking paste to a surface by constructing the dauber with bristles relatively short 105 and stiff because of the character of the paste, which, when used in connection with long, thin bristles, overcomes the flexibility of the bristles and forms a tuft of irregular shape. When the bristles are stiff and short 110 the consistency of the paste cannot distort the tuft of bristles as a whole. With such

a tuft the blacking may be rubbed vigorously over the surface whereafter the brush will resume its normal shape. By making the bristles stiff and short I am also enabled to 5 maintain a clear opening, as is best shown in Figures 1 and 2, which is in alinement with the tube 13 and central of the tuft, so that the humidifying element being also centrally disposed relative to said opening will 10 humidify the interior wall of said opening formed by the bristles. I am thus enabled to humidify the tuft interiorly and exteriorly, having a relatively thin wall of bristles to keep soft.

15 Extending longitudinally concentrical through the interior of the container is the feed screw 16 which is reduced in diameter at its upper extremity to form the annular shoulder 17, said reduced portion rotatably fitting the aperture 9 in the top 5 of the container and extending therethrough and formed at its upper extremity with oppositely disposed flat sides 18.

The feed screw is preferably formed with 20 left-handed threads 19 covering the major portion of the length thereof. The threads begin at a point spaced an appreciable distance from the shoulder 17, to thus leave a smooth shank portion 20 of uniform diameter extending downwardly from the underside of the top plate 5, wherein the feed screw is rotatable. At the base of the shank portion is the shoulder 21 formed by the threads. Resting upon said shoulder is the 25 circular washer 22 which latter loosely surrounds the shank portion and assists in supporting the humidifying element 23, which latter frictionally surrounds said shank portion to function as a packing to prevent air 30 which may enter through the aperture 9 to enter the interior of the container. The humidifier or wick fits frictionally in the bore of the container and is of a thickness to be held pressed flatly against the underside of the top plate by means of the 35 washer 22.

Centrally, the actuating cap 8 is perforated by an opening 24, adapted to receive the upper end of the feed screw and fit 40 against the sides 18 thereof so that when the actuating cap is revolved, the feed screw will be actuated. A fillister headed screw 25 fits the tapped hole 30 in the end of the feed screw and serves to firmly clamp the cap 45 against the shoulders 30 formed by the flattened sides 18. Thus, the cap is rotatably held in position by the shoulder 17 and the upper circular edge of the container, and may be termed a thumb piece whereby the 50 feed screw may be rotated.

At the lower end of the feed screw the threads discontinue at a point spaced sufficiently from the shoulder 10 to freely contain, therebetween, the piston 26, and the 55 leather under-facing 27 thereof, as indicated

in dotted lines in Fig. 3. The piston is formed with a hub 28 the bore 29 thereof being suitably threaded to fit the threads 19 of the feed screw. In operation, when the thumb piece is caused to be turned, the piston is fed downwards against the volume of paste composition 31, in the container thereby forcing it through the discharge opening 13 into contact with the bristles. The piston is prevented from turning in the 70 container by the horizontal rib 31, which latter extends into the notch 32 in the edge of the piston and the leather washer 27.

When the piston is disengaged from the feed screw it will rest upon the shoulder 10 formed by the sleeve (Fig. 3). When the piston is so disengaged, the thumb nut or actuating cap 8, will work noticeably so much easier as to constitute a signal to the user that no more blacking paste is being fed to the bristles. The magazine, or container may then be refilled by first restoring the piston to its initial position and then unscrewing the sleeve 2, when the container 80 may be conveniently filled.

For the purpose of further protecting the contents of the container against ingress of air, I provide the humidifying element 33, of material preferably similar to the elements 15 and 23 and which frictionally fits around the shank 20 and lies flatly on the top of wall 3. It further fits frictionally against the surrounding wall of the chamber 6 so that ingress of air through the joint between the aperture 9 and the shank 20 is effectively prevented.

Centrally the thumb piece 8 has a recess 34 to contain the head of the screw 25, to render the top of the dauber flat to enable it to be stood on end, which is a great convenience to the user.

It is to be understood that my device will be equally efficient in the use of any paste composition other than that used for shoes.

The present invention is an improvement upon the subject of Patent Number 1,342, 537, issued to me June 9, 1920 and filed Aug. 21, 1919.

I claim:

1. A dauber, comprising a hollow handle adapted to contain a paste composition, a bristle brush screw threaded in the end of said handle, to constitute a closure therefor, an aperture within the body of the bristles of the brush, said aperture being in open communication with the atmosphere and with the interior of the handle, and hand operable means for forcing the paste composition through said aperture, said means including a piston and member operatively connected to said piston extending through the wall of the handle, whereby said means may be actuated, and a humidifying element in the hollow of the handle back of said piston for the purpose set forth.

2. A dauber comprising a hollow handle adapted to contain a paste composition, a bristle brush screw threaded in the end of said handle to constitute a closure therefor, an aperture within the body of the bristles of the brush, said aperture being in open communication with the atmosphere and with the interior of the handle and hand operable means for forcing the paste composition through said aperture, said means including a piston, a rotary device operatively connected to said piston extending rotatably through the end wall of the handle, and an element of absorbent material back of said piston covering said end wall in the hollow of the handle and frictionally surrounding said device to thereby seal the joint between the latter and said end wall, said element also functioning as a humidifier to render the interior of the handle humid.
3. A dauber comprising a hollow handle adapted to contain a paste composition, a bristle brush protruding from the end of said handle, there being a passage extending through the body of bristles of said brush in open communication with the atmosphere and with the interior of the handle, an internal shoulder between said handle and bristle brush, hand operable means for forcing the paste composition through said passage onto the bristles of the brush, said means including a piston adapted to rest upon said shoulder and a revoluble feed screw having threaded engagement therewith whereby to feed the piston toward said passageway when the feed screw is revolved, said feed screw being formed to extend loosely through said piston when the latter
- is resting upon said shoulder to be held centered thereby.
4. A dauber comprising an elongated cylindrical hollow handle having an inset top wall said handle adapted to contain a paste composition, a brush protruding from the end of said handle, there being a passage extending through said brush into the interior of said handle, piston mechanism for forcing the paste composition through said passage, a part of said mechanism extending longitudinally through the top of the handle, a cap rotatably fitting over the top of said handle and secured to said extending part whereby to actuate said mechanism when said cap is rotated, and an absorbent material filling the space between said cap and inset top wall for the purpose set forth.
5. A dauber comprising an elongated cylindrical hollow handle having an inset top wall said handle adapted to contain a paste composition, a brush protruding from the end of said handle, there being a passage extending through said brush into the interior of said handle, piston mechanism for forcing the paste composition through said passage, a part of said mechanism extending longitudinally through the top of the handle, a cap rotatably fitting over the top of said handle and secured to said extending part whereby to actuate said mechanism when said cap is rotated, and an absorbent material occupying the space immediately above and below said inset top wall for the purpose set forth.

In testimony whereof I affix my signature.

HOWARD E. EVERETT.
